E. T. NOUALHIER.

Chimney Cowl.

No. 82,632.

Patented Sept. 29, 1868.

United States Patent Office.

EUGENE THÉODORE NOUALHIER, OF PARIS, FRANCE.

Letters Patent No. 82,632, dated September 29, 1868.

IMPROVEMENT IN CHIMNEY-COWLS.

The Schedule referred to in these Letters Patent and making part of the same.

TO ALL WHOM IT MAY CONCERN:

Be it known that I, EUGENE THÉODORE NOUALHIER, of No. 55 Rue Fontaine-au-Roi, Paris, department of the Seine, in the Empire of France, have invented "an improved apparatus for extracting or exhausting and expelling vitiated air, noxious exhalations, or deleterious vapors from dwellings or any other places;" and I do hereby declare that the following is a full and exact description thereof.

My apparatus is intended to apply on the tops of chimneys, or in any other position exposed to the wind, and to make the wind available in aiding the exhaustion of the smoke or other foul air from the flue or space below. It is provided with a vane which turns the upper portion, so that a free exit is provided on the leeward side. This general idea has been applied in various forms for many years, but never, so far as I am aware, in combination with the additional devices by which I promote its useful effect.

I will first describe what I consider the best means of carrying out my invention, and afterwards designate the points which I believe to be new therin.

The accompanying drawings form a part of this specification.

Figure 1 is a side elevation of the apparatus or ventilator complete, and

Figure 2 is a central vertical section.

The additional figures represent some of the details detached, and will readily explain themselves.

Similar letters of reference indicate like parts in all the figures.

A is a cylindrical casing, which is connected with the top of the chimney, or pipe, or flue which communicates with the rooms to be exhausted. B and C are tapering pipes, fixed around this pipe A. The upper edge of the lowermost tapering or nearly conical structure B, is joined directly to the exterior of the pipe A. The upper edge of the upper conical tapering pipe C is at a little distance off from the upper edge of the pipe A, so as to leave an annular space extending quite around. The wind approaching from either side, strikes in the space between the casings or pipes B and C, and is deflected upward through the annular space at the top. Vertical division-plates D are introduced in the space between B and C, which prevent the wind from blowing across, and compel it to be deflected directly upward.

A cylindrical extension, E, of the outer plate C, carries two cross-bars e e', which support a central pivot, f, on which is mounted a revolving cap by means of a hollow socket, as represented. The hollow socket is marked G, and the thin sheet metal of the lower portion of the cap is marked H. This is formed, as represented, so as to loosely enclose the fixed casing E at the bottom, and so as to provide an ample channel gradually deflected from the vertical to or near the horizontal direction, for the escape of the smoke or other foul air.

A proper vane, M, being provided to turn the revolving cap always with each change of wind, it will be readily understood that the smoke or foul air rising through the pipe A, is not only allowed a free egress on the leeward side of the revolving cap H, but is also aided in its progress by the more or less strong upward current, induced by the wind to flow through the annular space between the casing C and top of the pipe A. This current flows along between the foul air and the enclosing walls, and not only relieves the foul air from any resistance which might be due to friction against the enclosing walls, but powerfully aids it by interposing a thin stratum of air which is moving in the same direction as the foul air is required to move.

The exit of the gaseous matter from the hood above described is still further promoted by the additional parts represented.

I is a ring, or partial ring, of sheet metal, in the form of the frustum of a cone, mounted, as represented, on the revolving parts, so that it changes its position with each change of the latter, or, in other words, revolves with it. J is a wider ring, or partial ring, slightly conical in the opposite direction, and cut wider on the upper than on the lower side, so as to overhang, as represented. There is an annular space extending nearly around between the mouth of the inner hood H and the outer hood I J. The part I catches wind, and induces an active current through and around nearly the entire periphery of the discharge-mouth of the inner hood H. It follows that the escape of the gaseous matter from the inner hood H is still farther promoted by the divergence

or conical form of the part J, and by the presence of an active current of air between the inner and outer hood in the same direction as the discharged gases are to move. The overhanging of the part J at the final exit, defends the apparatus against the entrance of rain or snow under any conditions. If the final discharge were in the form represented for the hood H, without any external protection, it would be well adapted for the discharge of the gaseous matter, but when rain or snow should fall in a calm, a quantity would be liable to be received through its mouth.

The vane M is braced on each side by a rod or wire, m, and may be made larger or smaller, as may be required under any circumstances. I esteem it desirable to balance the revolving cap, by making the gravity of the vane very slight, and increasing the weight of the opposite side, so as to reduce the friction of the revolving parts to the smallest possible amount. It is desirable to make the entire revolving part turn with a very slight current of air.

The theory of my invention, in producing a partial vacuum in the pipe A, is analogous to that of many other exhausting-ventilators, but the form and arrangement of the parts give a superior effect in the several points above noted. I propose to employ the apparatus in every position where an exhaustion is required, and where a current of air, either the natural current of the atmosphere or any other, may be available.

Having now fully described my apparatus, what I claim as new, and desire to secure by Letters Patent, is as follows:

The tapering concentric pipes or cases B and C, arranged as represented, relatively to the flue A, and adapted to receive the wind and deflect it upward, as represented, the space between B and C being divided in compartments, and the entire apparatus combined with a revolving hood, substantially as and for the purposes herein set forth.

NOUALHIER.
